[57] CLAIM

The ornamental design for a head rail member for folding bed, as shown and described.

DESCRIPTION

FIG. 1 is a front elevational view of a head rail member for folding bed showing our new design, the left end being shown broken away for convenience of illustration;

FIG. 2 is a top plan view thereof;

FIG. 3 is a bottom plan view of the same;

FIG. 4 is a rear elevational view;

FIG. 5 is an end elevational view of one of the similar ends as seen in FIG. 1, in this case the left end; and

FIG. 6 is a transverse section taken on line 6—6 of FIG. 4.

FIG. 1.

FIG. 2.

FIG. 3.

FIG. 4.

FIG. 5.

FIG. 6.
